UNITED STATES PATENT OFFICE.

ROBERT ROTHMAN, OF BROOKLYN, NEW YORK.

KNIT FABRIC.

Application filed February 5, 1925. Serial No. 7,006.

One object of this invention is to produce a new form of double knit fabric, that will resemble a woven fabric, and embody the advantages of being practically non-stretchable in both directions, yet can be produced more economically, because a knitting machine has about five times the capacity of a loom.

Another object of the invention is to produce a double fabric that is interknit, yet the fabric produced can change at any time from a double fabric to either one of two fabrics alone, by simply omitting one or more of the threads fed to the needles and suitably controlling the needles and their cooperating sinkers.

A further object is to produce a double knit fabric in which one fabric will resist stretch or sag longitudinally, and the other fabric will resist stretch or sag transversely; whereby the knitting together of such two fabrics will eliminate stretch or sag in all directions in the fabric.

Another object of this invention is to produce a new form of double knit fabric that will show different effects or designs on the opposite sides, so that either side may be exposed in the article, and also in the article the pleat or turned edge can be used to produce different effects in the article; and which fabric on one face will have the effect of a woven fabric, while the opposite face will have a different effect, and be very similar to the outer face of the plain knit fabric.

A further object of the invention is to provide a fabric that will not produce a run upon one or more of the threads being cut or broken.

Another object of this invention is to provide a double fabric that is interknit, and in which a number of differently colored threads can be made to produce novel effects, and which can be varied by omitting one or more of the threads at certain parts of the fabric.

In the accompanying drawings showing one embodiment of my invention, Figure 1 shows the finished fabric.

Fig. 2 is a view of the rear side of the fabric.

Figure 3 indicates in a diagrammatic form an ordinary knit fabric.

Figure 4 indicates the fabric with the ordinary knit composed only of the float threads, omitting the plain loop thread.

Figure 5 indicates a method of knitting

my improved fabric shown from the outer side, but with the threads separated, the plain knit threads being indicated by broken lines and the float threads by full lines.

Fig. 6 is a diagrammatic view as it would appear at an edge of the fabric.

As shown in Figs. 3 and 4, the plain knit of circular or other form is produced by a single thread, three courses being indicated by 1, 2 and 3, each forming the usual needle wales and sinker wales. For each course 1 supply additional threads, three threads, 21, 22 and 23 being indicated, and which separately combine with the loops in the course 1, also in the similar manner in the courses in which the same three threads form other courses in the same manner. But these three extra threads are not all knit in with each of the wale loops, but each thread is knit in with spaced loops of the same course. As shown the thread 21 is knit in the loop 4 at 28 of the thread 1, forming a loop of two threads. Then the thread 21 is floated over the succeeding loops 5 and 6 of the thread 1, such float being indicated by 14; and this thread 21 is thereupon knit in with the loop 7 at 26 to form a two thread loop; thereupon floated at 17 over the loops 8 and 9, and knit in with the loop 10 at 29. In the same manner this thread continues to loop over two wales, and is knit in at the third loop, and every third loop thereafter. The second extra thread 22 does not knit in with the loop 4, but floats over it and is knit in the loop 5 at 27 to make the double thread loop. This thread 22 thereupon makes a long float 18, and is knit in with the loop 8 to form a double thread loop at 30. In the same manner this thread 22 forms a long loop 19 over loops 9 and 10, is knit in with the next loop, floats over the following two loops, and is knit in with the next loop in the same manner.

The third float thread 23 is floated over loops 4 and 5 at 20, and is knit in with the loop 6 at 31 to form a double thread loop. This thread 23 then floats at 24 over two loops 7 and 8, is knit in with loop 9 at 32 floats at 25 over two loops, and is knit in with the next loop. It will be thus seen that each of the loops 4 to 10 have a single one of the threads 21, or 22, or 23, knit in, and each of these is alternately floated over two wales, and knit in with the third wale; yet it will have but the single extra thread knit

in with it. The effect of such a fabric is that the main or outer face is formed almost entirely of float threads, that have a length of three complete wales in width. On the 5 back or reverse side the plain knit wales show each needle wale composed of a double thread that is woven rather tight. By this means is produced what is substantially a double fabric, that on the main side has the 10 appearance of the right side or outer face of an ordinary plain knit fabric. Yet these two fabrics are knit together and each strengthens and supports the other. This results in two great advantages in the fabric. 15 In the first place it is practically impossible for the fabric to produce what is known as a run; where a thread is cut or broken in the present fabric, a run will start that may easily extend the length of the fabric. This 20 new fabric can have one or more threads cut, or a hole made through the fabric, yet it will be impossible to cause a run.

Another great advantage is the elimination 25 of the tendency to sag or stretch. It has been found that dresses or other garments that are knit will stretch or sag merely by their own weight. This new fabric is proof against stretching in any direction. The float threads on one side will stop lateral stretching, and the double knit in the 30 opposite side will stop stretching in the longitudinal direction.

It has been further found that the fabric 35 of this kind which uses a single thread in the way of a plain knit, that is continued in each course, and the additional three float threads for each course or lay of the plain knit, can have the three threads stopped, and the plain knit continued, and then the 40 fabric resumed with the three float threads for each course; whereby bands of plain knit are combined with bands of the new fabric, in the continuous knit. It has been further found that in forming such a fabric, that the 45 plain knit can be stopped, and the three threads knit together that will produce the structure as indicated in Fig. 5, being composed of a plain knit loop with floats extending over two loops and knit in each third loop. Such fabric on the reverse side will 50 have single thread loops.

A fabric of this kind will be found to possess the desired extra weight without overloading with threads.

55 It has been found that in knitting my fabric as indicated in Figs. 1, 2 and 5, that the threads 1, 2 and 3 can be omitted at any time in the course of knitting, and the operation continued by using three float threads which will produce the fabric indicated in Fig. 4. This will form a continuous knit that will merge into the other form.

It is to be understood that I do not confine myself to three float threads or the exact arrangement or order of these threads but

reserve the right to use any such number or arrangement as will come within the scope claimed.

What I claim is:

1. A knit fabric comprising a series of 70 wales each consisting of interknitted loops, the thread from a loop of one wale being extended over at least one wale of the same course to form a float and interknit with a loop in a wale of the same course at least two loops distant from the first loop, the thread from a loop of the wale in the same course next the first wale being arranged in like manner and floated over the second loop to which the first thread is interknit whereby each loop is crossed by a plurality of float threads, each course also having a backing thread engaging all of the loops of the next succeeding course.

2. A knit fabric comprising a series of 85 wales each consisting of interknitted loops, the thread from a loop of one wale being extended over at least one wale of the same course to form a float and interknit with a 90 loop in a wale of the same course at least two loops distant from the first loop, the thread from a loop of the wale in the same course next the first wale being arranged in like manner and floated over the second loop to which the first thread is interknit 95 whereby each loop is crossed by a plurality of float threads arranged in regular staggered relation, each course also having a backing thread engaging all of the loops of the next succeeding course.

3. A knit fabric comprising a series of 100 wales each consisting of interknitted loops, the thread from a loop of one wale being extended over at least one wale of the same course to form a float and interknit with a 105 loop in a wale of the same course at least two loops distant from the first loop, the thread from a loop of the wale in the same course next the first wale being arranged in like manner and floated over the second 110 loop to which the first thread is interknit whereby each loop is crossed by a plurality of float threads arranged in regular staggered relation, all said float threads lying 115 entirely in the same course, and all of the wales being formed by equal numbers of threads whereby a flat unribbed fabric is formed, each course also having a backing thread engaging all of the loops of the next succeeding course.

4. A knit fabric comprising a series of 120 wales each consisting of interknitted loops, the thread from a loop of one wale being extended over at least one wale of the same course to form a float and interknit with a 125 loop in a wale of the same course at least two loops distant from the first loop, the thread from a loop of the wale in the same course next the first wale being arranged in like manner and floated over the second 130

loop to which the first thread is interknit whereby each loop is crossed by a plurality of float threads arranged in regular staggered relation, all said float threads lying 5 entirely in the same course, the number of threads in each course equalling one more than the number of wales jumped by the float threads whereby an equal number of threads are provided in each wale, each 10 course having a backing thread engaging all of the loops of the next succeeding course.

5. A knit fabric comprising a series of wales each consisting of interknitted loops, the thread from a loop of one wale being 15 extended over at least one wale of the same course to form a float and interknit with a

loop in a wale of the same course at least two loops distant from the first loop, the thread from a loop of the wale in the same course next the first wale being arranged 20 in like manner and floated over the second loop to which the first thread is interknit whereby each loop is crossed by a plurality of float threads, each course also having a backing thread engaging all of the loops of 25 the next succeeding course, the backing thread being of a different color to the remaining threads.

Signed at New York city, N. Y., on January 30th, 1925.

ROBERT ROTHMAN.
